BOX-SETTING DEVICE
John E. Morell, P.O. Box 191, Alpine, Tex.
Filed Oct. 31, 1963, Ser. No. 320,285
3 Claims. (Cl. 269—216)

This invention relates to a mechanical tool and, more particularly, to means for accurately installing an electrical switchbox.

In the construction of a house or other building having electrical services upon completion, numerous electrical switchboxes (such as the standard Raco, Steel City, or Bowers switchboxes) must be installed on the studs, two-by-fours, or other structural members prior to the installation of the wallboard, plaster, or other wall surface. These switchboxes must be secured in such manner that the outer surface, or opening, extends outwardly from the stud or other structural member a precise distance in order that its outer surface will be flush with the wall surface after it is installed. In this manner, when installed, the covering over the switchbox will not protrude from the wall, thus making it unsightly, nor "dig" into the wall.

In the average house most of these switchboxes are installed during its construction. Heretofore, much time was spent by the electrician, carpenter, or other artisan in installing these switchboxes. The alignment of the box and the extension of its outer surface has been done manually, and oftentimes had to be removed from the stud and re-aligned. Furthermore, the box, once aligned, had to be held by hand while it was being secured to the stud or other structural member by nails, or otherwise.

By my invention I have provided a device in which the switchbox may be held while being secured to the stud or other structural member and, simultaneously, which will permit proper alignment of the switchbox with respect to the stud, thus providing the desired extent of its protrusion from the stud.

It is, therefore, a principal object of my invention to provide means by which an electrical switchbox may be aligned with respect to the structural member of a building to which it is to be secured.

It is another object of my invention to provide means by which said switchbox can be held while being secured to said stud.

It is also an object of my invention to provide means by which the outer surface of said switchbox will extend the desired distance from said stud when secured thereto.

It is still another object of my invention to provide such means which will release said switchbox easily and simply when the switchbox has been secured to said stud.

It is also an object of my invention to provide such means by which the desired extension of the outer face of the switchbox with respect to said stud can be set.

Additional objects of my invention will be apparent from a study of the following disclosure and attached claims in conjunction with the drawings, wherein:

FIG. 1 is a perspective view of my invention.

FIG. 2 is an elevational view, in section, of my invention taken along the plane A—A of FIG. 1, including a cross-sectional view of the switchbox and stud.

FIG. 3 is a plan view of my invention.

FIG. 4 is an elevational view of the upper plate of my invention taken along the plane A—A of FIG. 1.

FIG. 5 is an end view of the upper plate shown in FIG. 4.

FIG. 6 is an end view of the lower plate of my invention.

STRUCTURE

My box-setting device is shown in FIGS. 1, 2, and 3. In FIG. 1 it is shown in the "open" configuration prior

2

to its being attached to a switchbox or after releasing same, as will be explained more fully hereinafter.

The principal structural members of my invention are: rod 13, platform 14, guide rods 15a, b, c, and d, upper plate 17, lower plate 18, tube 19, adjustment knob 22, lever 24, nut 25, and strap 26.

Referring to FIG. 2, device 10 is shown as it would appear in cross-section grasping switchbox 11 in position against stud 12, or other structural member for installation.

Platform 14 is a rigid plate to which is secured, by welding or other attachment remains, a plurality of guide rods 15a, b, c, and d. These rods extend upwardly from platform 14. Also, attached to platform 14 is rod 13 which is externally threaded for a purpose which will be described herebelow.

Lower plate 18, parallel to platform 14, contains a hole 18a which encircles rod 13 and a plurality of holes 18c through which guide rods 15 extend. Guide rods 15 are secured to platform 14 at 16a, b, c, and d respectively by welding or otherwise. Thus, platform 14, rod 13, and rods 15 can move perpendicularly to lower plate 18. As shown more clearly in FIG. 6, lower plate 18 is undercut as at 18b on both sides, thus providing a groove 18d.

Upper plate 17, as shown more clearly in FIGS. 4 and 5, has an end member 17a which is perpendicular to the main portion of upper plate 17. The main portion of the plate extending from the end member 17a backwardly therefrom has a downwardly and outwardly inclined surface 17c on each side of such proportions that main portion 17d can slide within groove 18d of lower plate 18 and surfaces 17c will match surfaces 18b. Thus, when portion 17d of the upper plate has been inserted (lengthwise) in groove 18d, upper plate 17 can move only longitudinally with respect to lower plate 18. It cannot move vertically with respect to lower plate 18.

Upper plate 17 contains a slot 17b. When it is inserted within lower plate 18 as previously described, slot 17b encircles tube 19 which is secured to lower plate 18 by welding or otherwise at 19a. As shown in FIGS. 1, 2, and 3 rods 15 are positioned outwardly of upper plate 17.

Tube 19 extends upwardly from lower plate 18 through slot 17b and encloses the upper portion of rod 13. It is secured to lower plate 18 at 19a by welding or otherwise. At the upper end of tube 19 is a flange 19c which contains a hole 19d, the purpose of which will be described hereinbelow. Extending downwardly into tube 19 is adjustment knob 22 which is internally threaded at 22b. The upper end 13b of rod 13 is threadedly connected within and to knob 22. Knob 22 contains a groove 22a into which protrudes ball 21 which is forced upwardly into groove 22a by spring 20 which is positioned within hole 19d. The purpose of this arrangement will be described hereinbelow.

Tube 19 contains a hole 19b which is threaded and through which extends screw 23. Screw 23 extends into groove 22c cut into knob 22 to prevent knob 22 moving vertically with respect to tube 19 when it is rotated relative to tube 19.

Lever 24 abuts tube 19 at 24b. The lower end 24a of lever 24 is contained within nut 25 in such manner that lower end 24a can move within and relative to nut 25. Lever 24 is maintained against tube 19 by strap 26 which is secured to tube 19 at 26a, shown more clearly in FIG. 1. Of course, lower end 24a of lever 24 can and does bear against nut 25 in operation.

OPERATION

As previously described, without reference to switchbox 11 or stud 12, the operator of my device 10 may grasp knob 22 and lever 24 in one hand and grip the

upper portion of lever 24 against knob 22. This forces nut 25, and hence upper plate 17, to the right (as shown in FIG. 2), thus forcing end member 17a against lower plate 18. Of course, upper plate 17 moves relative to lower plate 18 and, hence, relative to platform 14, rods 15a, tube 19, rod 13, and knob 22. A spring (not shown) may be inserted between flange 19c and lever 24 which, upon the operator's releasing his grip, would force lever 24 away from tube 19, thus forcing the lower end 24a of lever 24 in the opposite direction. This would force upper plate 17 to the left with respect to lower plate 18 and to the position shown in FIG. 1, thus leaving the gap 18c (FIG. 1) between end member 17a and lower plate 18.

To use device 10 lever 24 is forced to the right with respect to knob 22 (FIG. 2) to provide the space 18c between end member 17a and lower plate 18. Then, device 10 is placed over the outer portion of switchbox 11 (as shown in FIG. 2) and lever 24 is forced inwardly toward knob 22, as previously described. Now, switchbox 11 is gripped between end member 17a and surface 14a of platform 14. In this position it is held as in a vise and can be held against and secured to stud 12, or other structural member. However, prior to positioning switchbox 11, the distance between the outer surface 12a of stud 12 and the outer end 11a of switchbox 11 has been set.

The distance B—B between the outer surface 12a and the outer surface 11a is set in the following manner: Holding tube 19, and hence the entire device 10, firmly, knob 22 is rotated in the desired direction either to bring plate 14 closer to lower plate 18 or further therefrom. Since screw 23 protrudes into groove 22c, knob 22 will not move relative to lower plate 18; rather, upper end 13b of rod 13 will move within knob 22, thus moving platform 14 relative to lower plate 18, changing the distance B—B. Now, unless extra force is exerted on it, knob 22 will not move relative to tube 19 due to the pressure exerted on it by ball 21 and spring 20. Of course, notches can be provided within the upper portion of groove 22a to increase the resistance to such movement of knob 22.

Once the distance B—B has been established and set and switchbox 11 has been secured between end 17a and end 14a of platform 14, as previously described, platform 14 is positioned against stud 12 as shown in FIG. 2. Then, switchbox 11 is secured to stud 12 by nails extending through switchbox 11, or otherwise.

After this operation has been completed lever 24 is forced to the right (FIG. 2) with respect to knob 22, 50 manually or otherwise as previously explained. Then, box-setting device 10 is removed from contact with switchbox 11 and stud 12 and another operation is commenced.

In each of these operations it is apparent that the

distance B—B can be changed and the size of box 11 to be accommodated can be provided for.

From the foregoing it is seen that means have been provided by which an electrical switchbox may be aligned with respect to the structural member of a building to which it is to be secured.

Also, means have been provided by which the switchbox can be held while being secured to the structural member.

Further, means have been provided which the outer surface of the switchbox will extend the desired distance from the structural member when secured thereto.

Additionally, means have been provided by which the switchbox can be easily and simply released when it has been secured to the structural member.

Further, means have been provided by which the desired extension of the outer face of the switchbox, relative to the structural member, can be set.

It is to be understood that the form of the invention shown and described herein is to be taken as a preferred embodiment of same and that various changes in the shape, size, and arrangement of particulars may be resorted to without departing from the spirit of the invention or the scope of the attached claims.

What I claim and desire to secure by Letters Patent is:

1. A device for aligning an electrical switchbox on and with a building structural member comprising: A lower plate; an upper plate slidably contained in said lower plate having one end extending below said lower plate; a platform positioned below said lower plate having a plurality of guide rods extending upwardly through said lower plate; lever means connected to said upper plate to move said one end of said upper plate relative to said platform to releasably hold said switchbox between said one end of said upper plate and said platform; and adjustment means secured to said lower plate and co-acting with said platform for changing the distance between said platform and said lower plate.

2. The device of claim 1 wherein said upper plate and said lower plate contain aligned holes and said platform has screw means secured to its upper surface, said screw means extending upwardly through said aligned holes and co-acting with said adjustment means to change said distance.

3. The device of claim 1 wherein said lever means co-acts with said upper plate and said adjustment means to move said upper plate relative to said platform.
